UNITED STATES PATENT AND TRADEMARK OFFICE
Certificate

Patent No. D. 420.267

Patented: February 8, 2000

On petition requesting issuance of a certificate for correction of inventorship pursuant to 35 U.S.C. 256, it has been found that the above identified patent, through error and without any deceptive intent, improperly sets forth the inventorship.

Accordingly, it is hereby certified that the correct inventorship of this patent is: Nigel Robson, Gilesgate, United Kingdom; and Brian Wadge, United Kingdom.

Signed and Sealed this Thirteenth Day of May 2003.
